BUCKLE

Paul W. White, Waterbury, Conn., assignor to
Parva Products Company, Chicago, Ill., a cor-
poration of Delaware

Application August 5, 1938, Serial No. 223,159

1 Claim. (Cl. 24—194)

This invention relates to a buckle and has special reference to a slide buckle adapted to be mounted on a strap, band, or the like, for securing articles together or for the support of garments or other objects.

More particularly, this invention relates to a slide buckle for association with a strap comprising a pair of slidably engaged frames disposed in a face-to-face substantially parallel relation each having side bars and cross bars connecting the side bars for defining openings therethrough for receiving a strap, there being means for directing relative longitudinal movements of the frame with one cross bar of one of the frames co-operating with one of the cross bars of the other of the frames to clamp the strap threadable therebetween in adjusted positions upon relative longitudinal movement of the frames in one direction and a finger piece on one of the frames manually movable to cause relative longitudinal movements between the frames in the opposite direction to release the strap.

The device of the present invention may be adapted for use in various connections and, as a matter of fact, the construction may be employed with slight variations not departing from the spirit of this invention universally where detachable connections are described. Hereafter, and in the drawings, the device will be described and shown in its association with a strap for skates, books, and the like, although it is readily understood that the buckle may be employed with a strap for attachment to lingerie, for encircling the leg as a hose supporter, for use as a suspender, or for detachable engagement with garments of various characters. It is, of course, to be understood that various other uses may be mentioned and that this invention is not to be limited to any single specific use.

The buckle contemplated herein is adapted for use with a strap of leather, fabric, elastic, or any flexible material, and the strap may vary materially in thickness. The clamping action is preferably obtained automatically by the tension applied to the strap and retained in its use in securing skates on shoes, various articles together in a bundle, or as a suspender, garter, or the like, and an adjustment of the buckle to loosen the strap may be made with little effort by moving manually a finger piece on one of the frames.

As above stated, when tension is applied to the strap as in drawing up the strap to fit the strap tightly around the shoe, in securing skates thereto, a relative longitudinal movement of the frame is obtained and this movement directs co-op-

erating cross bars of the co-operating frames into engagement with each other to clamp the strap in position therebetween. This clamping engagement is held until a relative longitudinal movement between the frames in opposite directions is caused preferably by manual manipulation, one of the frames having a finger piece readily accessible for engagement.

In one form of the invention a finger piece is accessible through the strap opening of one of the frames, the finger piece being preferably formed integral with one cross bar of the other of the frames and in the other form the finger piece is formed as a rolled free edge of one cross bar of one of the frames readily accessible for engagement to tilt the frames with respect to the normal plane of the strap to cause relative longitudinal movement between the frames in an opposite direction to release the strap.

One of the objects of this invention is to provide a buckle having relatively slidable frame members of the type hereinabove described in which the strap threaded therethrough is automatically adjusted to a clamped position by a tension applied to the strap and is released from a clamped position by manual manipulation of a finger piece formed on one of the frames.

Another object of this invention is to provide a buckle having relatively slidable frame members as hereinabove pointed out in which a finger piece secured to and extending from one of the frame members is accessible for movement to release the strap from a clamped position through the strap opening of the other of the frames.

A further object of this invention is to provide a buckle having relatively slidable frame members of the type before described in which the strap is released from a clamped position by means of tilting a finger piece with respect to the normal plane of the strap to cause relative longitudinal movement between the frames.

It is also an object of this invention to provide a buckle having relatively slidable frame members of the character indicated above in which the construction is relatively inexpensive to manufacture, is durable, and is simple in construction, in threading, and in manipulation.

Other objects and advantages of this invention will be hereinafter more particularly pointed out and for a more complete understanding of the characteristic features of this invention reference may now be had to the following description when taken together with the accompanying drawings, in which latter:

Figure 1 is a front view of the buckle incorpo- 55

rating the features of this invention as shown in its relation with a strap;

Fig. 2 is an enlarged central sectional view of the buckle taken on the line 2—2 of Fig. 1 and 5 showing the strap in elevation;

Fig. 3 is a rear view of Fig. 1 showing a portion of the buckle in section;

Fig. 4 is a view similar to Fig. 2 showing a 10 changed position of the relatively slidable frame members;

Fig. 5 is a view similar to Fig. 2 of a modified form of buckle construction embodying the features of this invention;

Fig. 6 is a view similar to Fig. 5 showing a 15 changed position of the relatively movable frame members;

Fig. 7 is a front view of a modified form of buckle construction incorporating the features 20 of this invention, the buckle being shown in its relation with a strap;

Fig. 8 is an enlarged sectional view taken on the line 8—8 of Fig. 7, showing the strap in a clamped position in the buckle;

Fig. 9 is a view similar to Fig. 8 showing the 25 strap in a released condition;

Fig. 10 is a view similar to Fig. 7 of another modified form of buckle construction shown in its relation to a strap;

Fig. 11 is an enlarged sectional view taken on 30 the line 11—11 of Fig. 10 showing the strap in a clamped position between the frames of the buckle; and

Fig. 12 is a view similar to Fig. 11 showing the 35 strap in a released condition.

Referring now to the drawings and more particularly to Figs. 1 to 4, inclusive thereof, the construction therein shown as embodying the features of this invention comprises a pair of frame members 10 and 11, the frame member 10 being 40 substantially rectangular in shape and having spaced side bars 12 and 13 connected by spaced cross bars 14 and 15 to define a strap opening. The frame 11 is substantially rectangular in shape and has spaced side bars 16 and 17 connected by spaced cross bars 18 and 19 forming a 45 strap opening.

The frame 10 is provided with opposed flanges 20 and 21 with ledges 22 and 23 extending respectively therefrom inwardly in a direction toward 50 each other. The opposed flanges and ledges constitute opposed channels on the frame 10 for receiving the side bars 16 and 17 of the frame 11 for directing relative longitudinal movements of the frames.

The cross bar 14 of the frame 10 is preferably 55 inclined to provide an inclined strap-engaging face 24 extending between a rolled free edge 25 and an inturned ledge 26, the inturned ledge 26 defining the limit of movement of the frame 11 in one direction and the rolled free edge 25 presenting a fulcrum about which the strap may be 60 pulled in applying tension thereto.

The frame 11 is provided with an offset portion 65 27 which is preferably cut and deformed from the material thereof to provide the strap opening therein. The offset portion 27 co-operates with the inclined surface 24 to clamp a strap 28 in adjusted positions therebetween. A finger piece 29 is preferably formed integrally with the frame 70 11 and extends angularly relative to the normal plane of the frame in the direction of the opening of the frame 10 so that the finger piece is accessible through that opening.

The frame 10 is provided with a looped end portion 75 for receiving the free end of a strap threaded

through the openings of the co-operating frames 10 and 11, there being a raised cross bar 10a spaced from the end of the frame 10 connecting extensions of the side bars 12 and 13.

One end of the strap 28 is looped permanently 5 about the cross bar 15 of the frame 10 and the other free end of the strap 28 or a second strap is threaded through the opening of the frame 10 and between the offset portion 27 and the inclined strap-engaging face 24 of the frame 10. Tension 10 is applied to the free end of the strap 28 over the rolled edge 25 to clamp the strap under tension in a desired adjusted position. When it is desired to release the tension on the strap, the strap is lifted to the position in Fig. 4 and the finger piece 29 is engaged by the thumb or finger and moved in an opposite direction to that of the tensioning movement. The strap is thus released by manual manipulation.

Referring now more particularly to Figs. 5 20 and 6 of the drawings, the buckle shown therein comprises a pair of frame members 30 and 31, the frame 30 being substantially rectangular in shape and having spaced side bars 32 connected by spaced cross bars 33 and 34 to form a strap 25 opening. The frame 31 is likewise substantially rectangular in shape and comprises a pair of spaced side bars 35 connected by spaced cross bars 36 and 37.

The frame 30 is provided with opposed flanges 30a with ledges 30b extending therefrom inwardly in a direction toward each other. The opposed flanges and ledges constitute opposed channels on the frame 30 for receiving the side bars 35 of the frame 31 for directing relative longitudinal movements of the frames.

The cross bar 33 of the frame 30 is provided with rolled edges 38 and 39 with the under surface therebetween being inclined to form an inclined strap-engaging face 40. The frame 31 is 40 provided with an offset portion 41 preferably cut and deformed from the material thereof to form the strap opening of the frame 31.

A pair of ears 42 are bent downwardly and thereafter in a direction inwardly toward each other from the opposed ledges 30b to form a split cross bar extending laterally of the frame 30. A metal attachment 43 is looped about the cross bar 42, the opposed sides of the attachment extending beyond the cross bar to receive in a 50 clamped relation therebetween the end of a strap 44. In the particular attachment shown, prongs 45 are cut and deformed from the material of one of the sides of the metal attachment to penetrate the material of the strap and extend through 55 perforations in the other side of the metal attachment to be bent thereover for securing the end of the strap 44 against displacement therefrom.

The free end 44a of the strap is passed through 60 the opening of the frame 31 and between the offset portion 41 thereof and the inclined strap-engaging face 40 of the frame 30. Tension is applied to the free end of the strap in pulling the strap about the rolled edge 39 to obtain relative 65 longitudinal movement of the frames in one direction to clamp the strap in a fixed position. The free end is thereafter passed under the cross bar 34 and the buckle is in a clamped position relative to the strap with the free end being held 70 against creeping.

In order to release the strap from its clamped position, the free end of the strap is removed from beneath the cross bar 34 and the rolled edge 38 is engaged by the finger, as shown in Fig. 6, 75

to tilt the frame out of the normal plane of the strap about an axis provided by the cross bar 42 to cause relative longitudinal movement between the frames in a direction opposite to the clamping movement.

Referring now more particularly to Figs. 7, 8, and 9 of the drawings, the construction therein shown as embodying the features of this invention comprises a pair of frame members 46 and 47, the frame member 46 being substantially rectangular in shape having spaced side bars 48 and 49 connected by spaced cross bars 50 and 51 to define a strap opening. The frame 47 is substantially rectangular in shape and has spaced side bars 52 connected by spaced cross bars 53 and 54 to form a strap opening.

The frame 46 is provided with opposed flanges 55 having ledges 56 extending therefrom inwardly in a direction toward each other. The opposed flanges and ledges constitute opposed channels on the frame 46 for directing relative longitudinal movements of the frames.

The cross bar 50 of the frame 46 is preferably inclined to provide an inclined strap-engaging face 57 extending from a rolled free edge 58. The opposite edge of the strap-engaging face is cut away to form a slot 59 through which an extension 60 of the cross bar 53 of the frame 47 passes. The end of the extension 60 is upturned to provide a finger piece 61 for manually operating the frame 47 to release the strap from a clamped position.

A metal attachment 62 has a looped portion extending about the cross bar 51, the opposed sides being spaced to receive therebetween one end of a strap 63. Ears 64 are cut and deformed from the material of one side of the metal attachment to penetrate the material of the strap and pass through apertures in the opposed side of the metal attachment to be bent thereover for preventing displacement of the strap 63 therefrom.

The free end of the strap is threaded through the opening in the frame 47 and between an offset portion 65 thereof and the inclined strap-engaging face 57 of the frame 46. Tension is applied to the free end of the strap 63 over the rolled edge 58 to clamp the strap under tension in a desired adjusted position. The loose end 63a of the strap is thereafter inserted underneath opposed ears 66 formed from the material of the metal attachment and directed inwardly in a direction toward each other in a spaced relation from the metal attachment.

When it is desired to release the tension on the strap the finger piece 61 is engaged by the thumb or finger and moved in a direction opposite to that of the tensioning movement. The strap is thus released by manual manipulation for further adjustment or removal.

Referring now more particularly to Figs. 10, 11, and 12 of the drawings, the buckle therein shown comprises a pair of frame members 67 and 68, the frame 67 comprising a pair of looped portions 69 and 70 connected by side bars 71 and 72. The side bars 71 and 72 are connected by a cross bar 73 which is depressed below the normal plane of the frame. Ledges 74 are formed on the side bars 71 and 72 and extend inwardly in a direction toward each other in a spaced relation from the side bars 71 and 72 to form opposed channels. The looped portion 70

is raised above the normal plane of the frame and provides an opening for receiving the loose end of a strap 75. The looped portion 69 is provided with an inclined strap-engaging portion 76 on the under side of the material bounding 5 the loop opening.

The frame 68 has a substantially flat end portion 77 for engaging the opposed channels formed by the ledges 74 and side bars 71 and 72 to direct relative longitudinal movements of the frames. 10 The opposite end 78 of the frame 68 is inclined in the direction of the inclined face 76 of the frame 67, and, when in a clamped position, the end extends beyond the end of the cross bar 69. An opening 79 is formed intermediate the 15 inclined portion 78 and the substantially flat portion 77, and the material of the opening 79 is deformed to provide a strap-engaging ledge 80.

A metal attachment 81 is provided with a looped portion intermediate its ends, the ends being extended in a face-to-face position to receive therebetween the fixed end 75a of the strap 75. The end 75a of the strap is fixedly secured to the metal attachment by means of a rivet 82 extending through the strap and through an aperture in the opposed ends of the metal attachment. 20

The free end of the strap 75 is passed through the opening 79 and thereafter between the strap-engaging face 76 and the strap-engaging ledge 30 80 of the respective frames 67 and 68. Tension is applied to the free end of the strap to clamp the strap under tension in a desired adjusted position as shown in Fig. 11. The free end of the strap is thereafter inserted through the loop 35 of the frame underneath the bar 70 for use. When it is desired to release the tension on the strap, the extending portion of the cross bar 78 of the frame 68 is engaged by the thumb or finger and is moved in an opposite direction to that of 40 the tensioning movement.

While several embodiments of this invention are herein shown and described, it is to be understood that various modifications thereof may be apparent to those skilled in the art without departing from the spirit and scope of this invention and, therefore, the same is only to be limited by the scope of the prior art and the appended claim.

I claim:

A slide buckle comprising a pair of slidably engaged frames disposed in a face-to-face substantially parallel relation, said frames having side bars and cross bars connecting said side bars for defining openings therethrough to receive 55 a strap, means for directing relative longitudinal movements of said frames, and one cross bar of one of said frames being of substantially U-shaped cross section presenting spaced angularly extending legs and one cross bar of the other of 60 said frames having an inclined surface co-operating with one of said legs to clamp the strap threaded therebetween in adjusted positions upon relative longitudinal movement of said frames in one direction, the other of said legs forming 65 a finger piece accessible through said opening of the other of said frames for manual movement to cause relative longitudinal movement between said frames in the opposite direction to release said frames in the opposite direction to release the strap.

PAUL W. WHITE. 70
